1

Latin name of the genus and species of the plant claimed: *Malus domestica*.

DESCRIPTION OF RELATED APPLICATIONS

The new variety, 'FR1063' differs from other varieties in the following characteristics:

A. The fruit of the new variety is almost full red with a subtle stripe, ripening in early October, resembling no other known variety.

BACKGROUND OF THE INVENTION

A new and distinct variety of apple tree originating as a whole tree mutation of an *Malus domestica*, hereinafter referred to as 'FR1063'.

SUMMARY OF THE INVENTION

This new and distinct variety of apple tree was discovered in Conklin, Mich. as a whole tree mutation in an orchard planted in 1998. The new variety was noticed because the fruit was less red and started coloring about one week behind than the other trees in the orchard.

Observations during the next two seasons confirmed that the fruit and tree were completely different than the varieties surrounding it, including 'Gala', 'Honeycrisp', and 'Jonagold'. The mature fruit of the new variety finishes to a 40 to 50% red blush. The new variety matures in early October in central Michigan one to three weeks behind 'Gala', 'Honeycrisp', and 'Jonagold'.

In April of 2007, buds were taken from the original limb and reproduced by grafting on M9 (an unpatented selection) rootstock in Conklin, Mich. The new variety has remained true to the description herein contained. The new variety has not been grown on its own root.

DESCRIPTION OF THE DRAWINGS

The accompanying photographs show typical specimens of the new variety as depicted in color as nearly true as is

(57) **ABSTRACT**

A new and distinct variety of apple tree, 'FR1063', originating as a whole tree mutation of an unknown variety *Malus domestica*. This new variety is unique from other apple cultivars because of its coloring, flavor and ripening date.

reasonably possible in color illustrations of this character. These specimens were obtained at Chester Township, Conklin, Mich.

FIG. 1 illustrates the fruits and foliage of the new variety at maturity.

FIG. 2 illustrates blossoms and buds of the new variety.

FIG. 3 illustrates a dormant tree of the new variety.

FIG. 4 illustrates the trunk and lenticels of the new variety.

FIG. 5 illustrates a terminal bud of the new variety.

FIG. 6 illustrates a transverse and diagonal sections of the new variety.

DETAILED BOTANICAL DESCRIPTION

A detailed description of the 'FR1063' cultivar follows using The Royal Horticultural Society of London Colour Chart, 1986 edition, for color identification except where general color terms are sufficient.

20 Parentage: A whole tree mutation of unknown parentage.

Locality of the original discovery and observations is Chester Township, Conklin, Mich.

Tree:

25 *Age*.—5 years.

Size.—Large, height 2 m, width 1 m.

Vigor.—Vigorous, yearly growth averages 0.5 m.

Density.—Open.

Form.—Flat to slightly upright.

Production.—Very productive, averaging 800 bushels per acre.

Growth type.—Non-spur.

Bearing.—Annual.

Trunk:

35 *Size*.—85 mm in diameter at 90 cm above ground level.

Surface.—Smooth.

Bark color.—Gray 201D.

Lenticels.—Length 1 cm, width 1 mm.

Lenticel color.—Gray 201D.

<i>Lenticel density.</i> —1 per cm ² . Averaging 2 to 3 lenticels in an area of 4 cm×4 cm.		
Branches:		
3 year old branch.—20 mm in diameter, color Grayed Brown 199C.	5	<i>Pollination requirements.</i> —Requires pollen from other variety blooming in the same period.
2 year old branch.—10 mm in diameter, color Grayed Brown 199A.		<i>Pollen.</i> —Present, abundant.
1 year old branch.—6 mm in diameter, color Grayed Brown 199A.		<i>Flowers at popcorn stage:</i>
Lenticels: 0.1 mm in diameter, round, color Grayed Brown 199A.	10	<i>Pedicle.</i> —Length 19 mm to 22 mm, diameter 0.2 mm.
Leaves:		<i>Pedicel color.</i> —Grayed Green 195B.
Size.—Length 95 mm, width 55 mm.		<i>Bud.</i> —Length 9 mm, width 8 mm.
Texture.—Crisp, thin.		<i>Bud color.</i> —Red 43A.
Form.—Broadly ovate.		<i>Flowers at full bloom:</i>
Base.—Cuneate.		<i>Corolla diameter.</i> —Large, 75 mm to 85 mm when fully open.
Apex.—Acute.		<i>Numbers of flowers per cluster.</i> —3 to 5.
Upper surface pubescence.—Absent.		<i>Inflorescence type.</i> —Umbellate.
Lower pubescence.—Very fine.	20	Petals:
Upper surface color.—Green 139A.		<i>Arrangement.</i> —Overlapping, number 5.
Lower surface color.—Green 138A.		<i>Color.</i> —White 155D with a blush on 20% to 40% of the petal surface of Red 55B.
Leaf blade attitude in cross section.—Very cupped in a majority of leaves.		<i>Petal veins.</i> —Indistinct coloration of White 155A.
Leaf blade margin.—Straight with an occasional ripple.	25	<i>Shape.</i> —Rounded.
Venation.—Pinnate, 11 to 13 veins, mainly alternate, color Grayed Green 195B.		<i>Margin.</i> —Somewhat waved with an occasional point at the apex, cupped with a basin 5 mm deep from the edge to the center of the petal.
Mid-vein.—Upper surface color Green 145A, lower surface color Green 145A.		<i>Size.</i> —Length 30 mm, width 20 mm.
Margin.—Dentate.	30	<i>Texture.</i> —Crisp.
Petiole length.—32 mm.		<i>Pedicel.</i> —Length 27 mm to 28 mm, width 2 mm, color Yellow Green 145D.
Petiole width.—2 mm.		<i>Sepals.</i> —5 in number, wedge shaped, sharply pointed, length 5 mm, width 2 mm, color Yellow Green 145D.
Petiole upper color.—Grayed Green 195B.		<i>Filaments.</i> —Length 10 mm, width 0.3 mm, color White 155D at junction with anther.
Petiole lower color.—Green 144B.	35	<i>Anthers.</i> —Length 2 mm, width 0.1 mm, color Yellow 4C.
Petiole groove.—Very shallow, depth 0.1 mm at base of petiole.		<i>Pistil.</i> —Held slightly lower than anthers in a majority of blossoms.
Stipules.—Very fine, at the base of the petiole on most leaves.		<i>Ovary.</i> —Length 4 mm, width 1.5 mm, pubescent, color Green White 157A.
Stipule color.—Green 139A.	40	<i>Stigma.</i> —Width 1 mm, pubescent, color Green White 157A.
Leaf glands.—None observed.		<i>Style.</i> —Length 3 mm, width 1 mm, color White 157C.
Leaf buds:		Fruit:
Length.—2 mm.		<i>Maturity when described.</i> —Firm ripe.
Width.—2 mm.		<i>Date of picking.</i> —October 4 th to 7 th in Conklin, Kent County, Mich., generally harvested in two pickings.
Color.—Grayed Green 197B.	45	<i>Size.</i> —Axial diameter 80 mm, transverse diameter 95 mm.
Leaf bud shape.—Triangular, length 8 mm, width 7 mm.		<i>Fruit weight (firm ripe).</i> —250 g.
Placement on branch.—Opposite, spiral, applied.		<i>Form.</i> —Uniform, symmetrical, regular, blocky, round.
Internode distance.—20 mm to 25 mm on one-year old wood.	50	<i>Eye.</i> —Obtuse, deep, depth 19 mm, width 35 mm.
Pubescence.—Very faint.		<i>Basin.</i> —Symmetrical, abrupt at base, wide, depth, 21 mm, width 30 mm.
Growth pattern of one-year old shoots.—Held at a 90 degree angle to the trunk.		<i>Calyx.</i> —Open, segments persistent, erect, outer and inner surfaces Russet at calyx end: present in some fruit, extending to top of basin, pubescent, color Grayed Green 193A.
Spurs: Present on 2 year and older wood.	55	<i>Type of bearing.</i> —On spurs and long shoots.
Length.—10 mm to 15 mm.		Skin:
Width.—4 mm.		<i>Young fruit.</i> —Color at 20 mm size: Red 53 B.
Color.—Greyed Green 197A.		<i>Thickness.</i> —Medium thick.
Flowers:		<i>Texture.</i> —Very smooth, glossy with medium cuticle wax.
Bloom period.—Second week of May in central Michigan.	60	<i>Tendency to crack.</i> —Slight.
Presentation.—Showy.		<i>Lenticels.</i> —White, inconspicuous, small, few in number.
Fragrance.—Faint.		
Fertility.—Somewhat self-fertile, a good pollen source for other apple varieties blooming in the same period.	65
